UNITED STATES PATENT OFFICE

112,636

DESIGN FOR A METALLIC CONTAINER OR SIMILAR ARTICLE

Frank D. Goll and James K. Wareham, New Kensington, Pa., assignors to Aluminum Company of America, Pittsburgh, Pa., a corporation of Pennsylvania

Application April 6, 1938, Serial No. 76,326

Term of patent 14 years

To all whom it may concern:

Be it known that we, Frank D. Goll and James K. Wareham, citizens of the United States, residing at New Kensington, in the county of Westmoreland and State of Pennsylvania, have invented a new, original, and ornamental Design for a Metallic Container or Similar Article, of which the following is a specification, reference being had to the accompanying drawing forming a part thereof,

Fig. 1 is a plan view, Fig. 2 is a side elevational view, and Fig. 3 is a central sectional view of a metallic container or similar article embodying our new design.

We claim:

The ornamental design for a metallic container or similar article, as shown.

FRANK D. GOLL.
JAMES K. WAREHAM.
